(57) **CLAIM**

We claim the ornamental design for a wet wipe dispenser, as shown.

DESCRIPTION

FIG. 1 is a top front perspective view of a wet wipe dispenser showing our new design;

FIG. 2 is a top view thereof;

FIG. 3 is a front view thereof;

FIG. 4 is a side view thereof;

FIG. 5 is a back view thereof;

FIG. 6 is a bottom rear perspective view thereof;

FIG. 7 is another top front perspective view thereof; and,

FIG. 8 is a bottom view thereof.

1 Claim, 4 Drawing Sheets
